UNITED STATES PATENT OFFICE.

CHARLES E. GILBERT AND ANDROV H. CARLSON, OF BRIDGEPORT, CONNECTICUT.

TOY DUMP CART OR WAGON.

1,390,122.

Specification of Letters Patent. Patented Sept. 6, 1921.

Application filed April 8, 1920. Serial No. 372,140.

To all whom it may concern:

Be it known that we, CHARLES E. GILBERT and ANDROV H. CARLSON, citizens of the United States, residing at 293 William St., Bridgeport, and Fairfield Ave., Bridgeport, county of Fairfield, State of Connecticut, have invented an Improvement in Toy Dump Carts or Wagons, of which the following is a specification.

10 The present invention provides a novel toy which is simple in structure, attractive in appearance, and cheap to manufacture, and one which is especially suitable for the amusement of children.

15 With the above and other objects in view, the invention consists of the construction and arrangement of parts as now to be fully described and hereinafter specifically claimed.

20 In the accompanying drawing forming a part of this specification,

Figure 1 is a side elevation of the novel toy;

25 Fig. 2 a longitudinal sectional view; and

Fig. 3 is a side elevation of a modified form.

30 The running gear of the toy dump cart or wagon of the invention may be of any ordinary or preferred form. As shown in Figs. 1 and 2, it consists of side strips 10 of metal which are connected by cross strip 11 near the front of the wagon and by a U-shaped bracket 12 near the rear thereof. The rear 35 wheels and the body of the wagon are pivoted to the arms of U-shaped bracket 12, sides 13 of the body having riveted to them reinforcing strips 14 for this purpose. The front ends of the side strips are turned up- 40 wardly and shaped as shown to provide a support for the seat of the wagon. Beneath the seat there is a second cross strip 15 which connects the front ends of the side strips to each other, and pivoted to the middle 45 point of cross strip 15 is a U-shaped supporting member 16 for the seat of the wagon. The arms of supporting member 16 extend

downwardly and are connected to opposite ends of a cross supporting strip 17 having 50 downwardly turned ears 18 in which the axle for the front wheels is pivoted. A tie clamp 19, shaped as shown, is provided, and has its rear end attached to the midlength of cross strip 11 and its front end pivotally attached 55 to the midlength of supporting strip 17 by means of a rivet 20. Also attached to the supporting strip, on either side of rivet 20,

are the inner ends of converging strips 21 the outer ends of which pivotally carry a handle 22. It will be seen that the axle for 60 the front wheels can be turned to any angle without interference from the tie clamp. The tie clamp serves two functions. It acts as a brace for the seat, as will be apparent, and it carries spaced apart struck up ears 23 65 for a purpose to be explained. Converging strips 21 carry a shaped bracket 24 the purpose of which will be made apparent.

25 denotes a dumping lever which is pivotally attached to the outer end of the handle as indicated at 26, and 27 denotes a link which is pivoted at its outer end to the dumping lever and at its inner end to bell crank lever 28 the pivot point 29 of which is in shaped bracket 24. A second bell crank 70 lever 30 is pivoted between struck up ears 23. As more clearly shown in Fig. 2, the rearwardly extending arm of bell crank lever 28 and the forwardly extending arm 75 of bell crank lever 30 are adapted for attachment to each other. For this purpose, each of the arms just mentioned is provided with an elongated, longitudinal slot. A double headed rivet 31 passes loosely 80 through the slots. It will be apparent that by connecting the bell crank levers in the manner described these levers can be turned to any desired angle with respect to each other. That is, the handle, the front axle and bell crank lever 28 can be turned to any 85 angle with respect to the wagon body without interference from bell crank lever 30. The rear arm of bell crank lever 30 pivotally carries one end of a link 32 the other end of which is pivotally connected to the mid-length of a spindle 33. Opposite ends of 90 the spindle pivotally carry the inner ends of toggle arms, denoted by 34, 35 and 36, respectively. The outer ends of the toggle arms are pivotally attached to opposite sides 95 of the body, to opposite ends of pivoted tail gate 37 on the body, and to the side strips of the running gear, as indicated at 38, 39 and 40, respectively.

100 The manipulation of the dump wagon disclosed in Figs. 1 and 2 will be apparent without further description. When the dumping lever is grasped and drawn to the position of Fig. 2, the rearwardly extending arm of bell crank lever 28 and the forwardly extending arm of bell crank lever 30 will be forced upwardly, as will be obvious. As has 105 already been suggested, this will be so no matter what may be the angular position of

the front axle with respect to the body of the wagon. When the forwardly extending arm of bell crank lever 30 is elevated, the rearwardly extending arm thereof will be lowered. Link 32 and spindle 33 will consequently be forced rearwardly, and the toggle arms will be caused to spread to tilt the wagon body and to force the tail gate to swing on its pivot. When the dumping lever is returned to the position of Fig. 1, the action will be the reverse. As shown, the body is pivoted to the running gear at a point to the rear of the middle portion of the body, so that when in the position shown in Fig. 1, the front portion of the body will rest on spindle 33.

In the modified form of Fig. 3, the cart body is pivoted to the running gear as in the preferred structure. A pivoted tail gate 41 is provided, and arms 42 are pivoted to the tail gate and to the axle or some part of the running gear. Side strips 43 of the running gear are inwardly bent to extend toward each other, as indicated at 44, and the inwardly bent portions merge into a handle 45. The side strips are connected to each other and thus braced, by a cross strip having upturned arms 46 which carry a spindle 47 at their upper ends. A bell crank lever 48 is pivotally attached to the midlength of spindle 47 and has its lower arm pivotally attached to a link 49. The outer end of this link pivotally carries a dumping lever 50 which is arranged on the upper side of the handle to have sliding movement thereon. For this purpose dumping lever 50 is provided with longitudinal slits 51. Double headed rivets 52, passing through the slits and the handle, hold the dumping lever to the handle. The outer end of the other arm of bell crank lever 48 is provided with a cross pin 53. At the front of the bottom of the cart body and located near the longitudinal center of said bottom, are two spaced apart sliding brackets 54 which are arranged lengthwise on the body and are parallel to each other. The forwardly extending arm of the bell crank lever lies between the sliding brackets, and the cross pin has its ends extending into and beneath the brackets, as will be understood. The sliding brackets thus guide the cross pin and limit its longitudinal movement on the bottom of the cart body. 55 denotes a supporting foot for the cart.

The operation of the toy of Fig. 3 will be apparent. To dump the cart body, the dumping lever is moved from the position shown in full lines to that shown in dotted lines. The downwardly extending arm of the bell crank lever will be pulled forwardly and the arm which is engaged with the sliding brackets will be elevated to tilt the body, the cross pin sliding from front to rear of the sliding brackets. As the cart body is

pivoted to the running gear at a point to the rear of its middle, when the dumping lever is returned to the full line position of Fig. 3 the body will rest on spindle 47. When the body is made to tilt as just described, its rear end will move to a point closer to the axle than when the body was in horizontal position, while arms 42 will rotate on the axle. Consequently, the rear end of the body will be moved away from the tail gate. That is, the tail gate will be swung on its pivot and away from the cart body, as it is shown in dotted lines in Fig. 3.

What we desire to claim is:

1. A toy dump cart or wagon, comprising a running gear having a body and a handle pivoted thereto, a tail gate pivoted to the body, a dumping lever pivoted to the handle, toggle arms, and means connecting the toggle arms with the dumping lever, said connecting means including bell crank levers adjacent arms of which are loosely connected so that said levers may have angular movement with respect to each other, whereby said dumping lever may be actuated to tilt said body and throw said tail gate on its pivot regardless of the relative angular positions of said bell crank levers.

2. In a toy dump cart or wagon, a running gear having a body and a handle pivoted thereto, a tail gate pivoted to the body, a dumping lever pivoted to the handle, toggle arms, means connecting the toggle arms with the dumping lever, said connecting means including bell crank levers adjacent arms of which are provided with longitudinal slots, and a double headed rivet passing through said slots and loosely holding said adjacent arms to each other.

3. I a toy dump cart or wagon, the combination of a body, a tail gate, a running gear, dumping mechanism extending between the body and the tail gate and the running gear, a handle for maneuvering the cart, a dumping lever thereon and means whereby the body and tail gate may be moved to dumping position by movement of the dumping lever in the direction of travel of the cart while the cart or wagon is in motion.

4. In a toy dump cart or wagon, a body, a running gear, steering mechanism, a handle attached to the steering mechanism, dumping mechanism extending between the running gear and the body, and a dumping lever carried by the handle and pivotally connected to the dumping mechanism whereby the body may be moved to dumping position regardless of the angle between the cart and the handle.

In testimony whereof we affix our signatures.

CHARLES E. GILBERT.
ANDROV H. CARLSON.
